UNITED STATES PATENT OFFICE.

ADOLPH SCHRETER, OF BALTIMORE, MARYLAND.

NECKTIE.

Application filed June 21, 1923. Serial No. 646,857.

To all whom it may concern:

Be it known that I, ADOLPH SCHRETER, a citizen of the United States, residing at Baltimore, and State of Maryland, have invented a new and useful Necktie, of which the following is a specification.

This invention relates to neckties and more particularly to neckties of the bow type.

10 The primary object of the invention is to provide novel means for holding the wings of a bow tie in predetermined positions, eliminating any possibility of the bow tie becoming wrinkled or out of shape.

15 Another object of the invention is to provide a device of this character which will not interfere with the construction of the tie, and one which may be readily and easily positioned, during the manufacture of 20 the tie.

With the foregoing and other objects in view which will appear as the description proceeds, the invention resides in the combination and arrangement of parts and in 25 the details of construction hereinafter described and claimed, it being understood that changes in the precise embodiment of the invention herein disclosed, may be made within the scope of what is claimed, without departing from the spirit of the invention.

Referring to the drawing:

Figure 1 is an elevational view disclosing a made-up bow tie constructed in accordance with the invention, a portion of the cloth forming the tie being broken away.

Figure 2 is a view disclosing the stiffening member as secured to the felt lining employed in tie construction.

40 Figure 3 is a view disclosing the stiffening member, a portion of the cover thereof being broken away to illustrate the wire stiffening elements.

Figure 4 is an edge elevational view 45 thereof.

Figure 5 is a fragmental detail view disclosing the stiffening member as partly broken away, to illustrate the wires.

Referring to the drawing in detail, a tie 50 constructed in accordance with the present invention, embodies a forward section including lateral wings 5 and a rear section including lateral wings 6, all of which sections are united by the tying member 7.

The reference character 8 indicates a strip 55 of felt padding extensively used in cravat manufacture, to which padding is secured the stiffening member forming the essence of the present invention.

This stiffening member is indicated generally by the reference character 9 and embodies a length of cloth material of a tubular nature in which are positioned the stiffening elements 10, which are in the form of wires disposed along the edges of the cloth 60 material. As shown, the ends of the stiffening member are bent inwardly, eliminating any possibility of the wires extending through the tubular member to cause undue wear on the cloth material of which the tie 65 is formed.

In the manufacture of a tie in accordance with the present invention, the padding material 8 together with the stiffening member which is shown as secured to the padding 8, 70 by a line of stitching 11, is positioned in the cloth material of which the tie is constructed, whereupon the cloth material together with the felt padding is folded inwardly to form the wings of the tie, the side 75 edges of the stiffening member lying appreciable distances from the side edges of the wings of the tie to permit portions of the wings to droop simulating a hand-tied cravat.

It will readily be seen that if the user should desire to bend the wings of the tie forwardly, the wings would be held in such position by the wires 10, which are formed of pliable material.

I claim:

In a necktie construction, a body portion, a necktie interior for positioning in the body portion and including a padding strip, a reinforced fabric stiffening member secured 85 to the padding strip and the edges of the fabric stiffening member being substantially spaced from the edges of the padding strip, to allow the edges of the body portion to bend.

In testimony that I claim the foregoing as my own, I have hereto affixed my signature in the presence of two witnesses.

ADOLPH SCHRETER.

Witnesses:

IVY E. SIMPSON,
AGNES ROCKELLI.
